UNITED STATES PATENT OFFICE.

ALBERT NELSON, OF CHICAGO, ILLINOIS, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,199,101.

Specification of Letters Patent. Patented Sept. 26, 1916.

Application filed October 5, 1915. Serial No. 54,118.

To all whom it may concern:

Be it known that I, ALBERT NELSON, a citizen of the United States, and a resident of Chicago, in the county of Cook and State 5 of Illinois, have made and invented certain new and useful Improvements in Brake-Shoes, of which the following is a specification.

My invention relates to reinforcing backs 10 for brake shoes, and concerns in particular the construction of the attaching lug, and its mode of securement and anchorage to the back proper.

It is an object of my invention to provide 15 a separate attaching lug which is so formed and constructed, that the reinforcing cast metal, which ordinarily extends up from the body of the shoe and around the lug so as to reinforce and supplement the same, is rendered unnecessary and is omitted, whereby 20 a material saving of cast metal is effected and the weight of the shoe, when scrapped, is materially reduced.

A further object is to provide a brake shoe 25 back having a separately formed box-shaped lug of such configuration and arrangement as to prevent its becoming broken or crushed, either during transportation or while in service.

30 A further object is to provide an improved securement and anchorage between the lug and the back, whereby the lug is securely held in the direction of the length of the back.

35 Other objects and advantages will appear as the description proceeds, it being understood that changes in the precise embodiment of my invention can be made within the scope of what is claimed, without departing from the spirit thereof.

The preferred embodiment of my invention is disclosed in the accompanying drawings, wherein:—

40 Figure 1 is a view in side elevation of the reinforcing back and the attaching lug secured thereto, the foregoing embodying the characteristic features of my invention; Fig. 45 2 is a top plan view of the same; Fig. 3 is a view in transverse vertical section of a brake 50 shoe, in which the reinforcing back and attaching lug are anchored; Fig. 4 is a view in perspective of the blank from which the lug is formed; and Fig. 5 is a view in perspective of the finished lug and, for the purpose

of clearness, illustrating the same unaccompanied by the reinforcing back.

Referring specifically to the several views, the separately formed attaching lug is stamped from a single blank, illustrated in its preferred embodiment in Fig. 4, which blank includes the top portion 12, attaching end wall portions 13, and the side portions 14, the latter being enlarged toward their outer extremities and provided with confronting U-shaped slits 15 therein. By the action of suitable dies, the blank is bent into the box-shaped lug, illustrated in Fig. 5, which includes the attaching end walls 13', the side walls 14' and the top 12'. The end walls, which, in common with the side walls, are 60 formed as a part of the top, project down between the said side walls and brace and hold them against crushing and distortion. The tongues 17, formed by the confronting slits 15, are inwardly and upwardly bent against 65 the top 12', thus defining keyway openings and, at the same time, providing an additional thickness of metal at the top of the lug. Should it be so desired, the tongues 17 may be entirely removed and the side walls 70 of the lug provided with the regular keyway openings therein. The end walls 13' of the lug are formed considerably longer than the side walls, and the extremities thereof are bent beneath and against the reinforcing 75 back plate, thus securely anchoring the lug thereto. The lug, as thus constructed, may be used with the ordinary type of steel reinforcing back. The special form of back 80 illustrated in the drawings, is provided with and contains T-shaped slits (not shown) at 85 its sides, the resulting flaps 11 being bent outwardly and above the plane of the back, to thus form anchoring and holding flanges. The formation of the holding flanges 90 reduces the width of the central portion of the back to the required amount, and this reduced portion is preferably crimped in an outward direction, so that the extremities of the end walls of the lug, which are bent therebeneath, are disposed in or above the general plane of the back. The lower extremities of the sides 14' rest upon the reinforcing back 10 and receive therebetween, and contact with, the holding flanges 11,

100 which in this form of construction, extend between the side and end walls of the lug, whereby the lug is securely anchored against 105

movement in the direction of the length of the back.

The reinforcing back and attaching lug are placed within a suitable mold, and the 5 wearing body 18 is cast thereon, the molten metal of which, however, does not, necessarily, flow or extend above the general plane of the back at the lug attaching portion, as the construction of the lug and reinforcing back renders unnecessary additional securing means for holding the two together. The foregoing effects a material saving in metal over the usual form of 10 brake shoe, wherein the cast metal, of necessity, flows up and around the attaching lug to supplement the same and to strengthen the securement between the lug and the brake shoe back. The inward turning of 15 the tongue 17 presents a smooth bearing for the shoe attaching key, and also brings the top wall of the key opening the standard distance from the top of the lug, without the use of excessively heavy metal in the construction of the lug itself.

20 25 What I claim is:—

1. A brake shoe lug, comprising connected sides and top, attaching arms connected to said top projecting between said sides and with the ends thereof being bent to engage a brake shoe back, said sides provided with U-shaped slits therein defining tongues connected to the top of said lug, said tongues being bent inward beneath and into contact with the lower surface of said top.

2. An article of the class described comprising a reinforcing back with upstanding holding flanges adjacent the central portion thereof, an attaching lug including a top and sides, the said sides contacting with 30 40 and reinforced by said holding flanges, attaching arms carried by said top projecting between said holding flanges and engaging the under surface of said reinforcing back, said sides provided with key openings 45 therein.

3. A brake shoe comprising a reinforcing back with outstanding holding flanges adjacent the central portion thereof, an attaching lug formed with a top and spaced 50 sides, with the sides thereof contacting with the said holding flanges, said sides provided with U-shaped slits therein, and with the resulting tongues being bent into contact with the inner surface of said top, at-

taching arms connected to said top, contacting with said holding flanges and anchored to said back, and a wearing body anchored to said back.

4. A brake shoe comprising a reinforcing back with a reduced and outwardly crimped central portion, outstanding holding flanges formed integral with said back, and resulting in the reduction in width of said central portion, an attaching lug formed with a top and connected sides, said sides formed with key openings therein and contacting with said holding flanges, attaching arms carried by said top projecting between said holding flanges and engaging the under surface of the crimped portion of said back, and disposed above the lower surface of said back, and a wearing body anchored to said reinforcing back.

5. A box-shaped brake shoe lug comprising a top, side walls carried thereby and 75 provided with key openings therein, end walls connected to said top and projecting between said side walls, and means carried by said walls adapted to engage a brake shoe back and anchor the lug thereto.

6. A brake shoe lug comprising a top, overlapping end and side walls carried thereby, said side walls provided with key openings therein, and said end walls projecting beneath said side walls and adapted 85 to engage a brake shoe back and anchor the said lug thereto.

7. A box-shaped brake shoe lug consisting of connected top, end and side walls, said side walls projecting between and beyond 90 said end walls and provided with key openings therein, and attaching means carried by said walls.

8. A reinforcing back for brake shoes, a lug anchored thereto and consisting of a top, 95 end and side walls connected to said top, with the side walls provided with key openings therein and projecting between said end walls, attaching means carried by said wall, engaging said back.

Signed at Chicago, in the county of Cook and State of Illinois, this 2nd day of October, A. D. 1915.

ALBERT NELSON.
